(57) **CLAIM**

The ornamental design for a boom truss panel for agricultural machine, as shown and described.

DESCRIPTION

FIG. 1 is a perspective view of a boom truss panel for agricultural machine according to our new design;

FIG. 2 is a first side elevational view thereof;

FIG. 3 is a second side elevational view thereof;

FIG. 4 is a first plan view thereof;

FIG. 5 is a second plan view thereof;

FIG. 6 is a first end elevational view thereof, shown enlarged for clarity;

FIG. 7 is a second end elevational view thereof, shown enlarged for clarity;

FIG. 8 is a sectional view thereof taken along line 8-8 of FIG. 2;

FIG. 9 is a perspective view showing a boom truss panel for agricultural machine according to another embodiment of our new design having a mirror image orientation as compared to FIG. 1; and,

FIG. 10 is a first side elevational view thereof, all other views being mirror images of FIGS. 3-8 above.

The broken line representations in the figures depict unclaimed environment and form no part of the claimed design.
